(57) CLAIM

The ornamental design of a snowmobile foot hold, as shown and described.

DESCRIPTION

FIG. 1 is a perspective illustration, from the front and the right side, of a first variant of the snowmobile foot hold of the design;

FIG. 2 is a right side view thereof;

FIG. 3 is a left side view thereof;

FIG. 4 is a rear view thereof;

FIG. 5 is a front view thereof;

FIG. 6 is a top view thereof;

FIG. 7 is a bottom view thereof;

FIG. 8 is a perspective illustration, from the front and the right side, of a second variant of the snowmobile foot hold of the design;

FIG. 9 is a right side view thereof;

FIG. 10 is a left side view thereof;

FIG. 11 is a rear view thereof;

FIG. 12 is a front view thereof;

FIG. 13 is a top view thereof; and,

FIG. 14 is a bottom view thereof.

In certain variants, where included, broken lines are for illustrative purposes only and form no part of the design.
